(57) CLAIM

The ornamental design for a knife block, as shown and
described.

DESCRIPTION

FIG. 1 is a top view of a knife block.

FIG. 2 is a front view of the knife block.

FIG. 3 is a right view of the knife block.

FIG. 4 is a back view of the knife block.

FIG. 5 is a bottom view of the knife block; and,

FIG. 6 is a left side perspective view of the knife block.

The broken lines in the figures are for environmental pur-
pose only and form no part of the claimed design.
